(57) **CLAIM**

The ornamental design for a ring setting, as shown and described.

DESCRIPTION

FIG. 1 is a perspective view of the ring setting; FIG. 2 is a bottom view of the ring setting shown in FIG. 1; FIG. 3 is a top view of the ring setting shown in FIG. 1; FIG. 4 is a front view of the ring setting shown in FIG. 1; FIG. 5 is a rear view of the ring setting shown in FIG. 1; FIG. 6 is a left view of the ring setting shown in FIG. 1; and, FIG. 7 is a right view of the ring setting shown in FIG. 1. The gems having hatch marks are black; the gems with no hatch marks are white. The broken line showing of the ring-portion is for illustrative purposes only, and forms no part of the claimed design.
